ATTORNEY

UNITED STATES PATENT OFFICE.

ROBERT P. MORTON, JR., OF FAIRVIEW, NEW JERSEY.

DRAPEY-HANGER.

1,388,054.

Specification of Letters Patent. Patented Aug. 16, 1921.

Application filed October 23, 1920. Serial No. 418,992.

To all whom it may concern:

Be it known that I, ROBERT P. MORTON, Jr., a citizen of the United States, residing at Fairview, in the county of Camden and State of New Jersey, have invented new and useful Improvements in Drapery-Hangers, of which the following is a specification.

This invention relates to drapery hangers in general and has more particular reference 10 to what are usually termed crape hangers.

The present method employed by undertakers in hanging crape consists in driving a nail or screw into the support and subsequently hanging the crape on said nail by 15 means of strings or other suitable flexible elements. This not only requires considerable time, but is a source of annoyance in both hanging the crape or removing the same from its support.

20 It is therefore the purpose of this invention to provide a device which is very simple in construction for hanging crapes on a suitable support to overcome the above noted objections by the present day method, and 25 providing a device that can be manufactured and sold at a very nominal cost.

The nature and advantages of the invention will be better understood when the following detailed description is read in connection with the accompanying drawing the 30 invention residing in the combination, construction and arrangement of parts as claimed.

Figure 1 is a perspective view of the plate 35 member.

Fig. 2 is a perspective view of the complete device showing the fastening element attached to the plate member.

In the drawings forming part of this 40 application like numerals of reference indicate the similar parts in the several views and wherein:

The device forming the subject matter of my invention embodies an elongated member or plate 10 which may be constructed 45 from any suitable material and which is slit along parallel lines as at 11 at spaced points in its length, the spaced portions of the material thus defined provides bendable 50 tongues 12. The bendable tongues 12 pro-

ject in opposite directions transversely of the plate and from a point approximately in a plane with the longitudinal center of the plate. The plate is also provided at one end with a longitudinally disposed slot 13. 55 At one side of the plate is arranged a fastening element for associating the crape with the plate the fastening element in this particular instance in the form of a safety pin 14. The fixed element of the pin is arranged 60 against one side of the plate and held in position thereon by means of the bendable tongues 12, the said tongues being bent to provide loops which embrace said fixed limb of the pin as shown. It is thereby understood 65 that the device in its entirety may vary in size and may also be constructed of any suitable design, and when it is desired to hang a crape it is only necessary to position the plate 10 upon a screw-eye or other 70 suitable element (not shown) in which element is received by the slot 13 of the plate. Manifestly, the plate assumes a vertical position when in use and cannot become casually separated from the nail or other fastening 75 element. It is also obvious that the crape can be easily and quickly associated with the safety pin or removed therefrom as the occasion requires.

While it is believed that from the foregoing description the nature and advantages of the invention will be readily apparent, I desire to have it understood that I do not limit myself to what is herein shown and described, and that such changes may be 80 resorted to when desired, as fall within the scope of what is claimed.

What I claim is:

A crape hanger comprising an elongated member having a longitudinally disposed 90 slot arranged adjacent one end of the member, bendable tongues provided on said member and formed to provide loops arranged in aline with said slot, and safety pin having a body portion thereof embraced by said 95 loops for holding the pin mounted on one side of said member.

In testimony whereof I affix my signature.

ROBERT P. MORTON, JR.
